UNITED STATES PATENT OFFICE.

OTIS A. MYGATT, OF NEW YORK, N. Y.

DESIGN FOR A GLASS SHADE.

44,613.

Specification for Design.

Patented Sept. 2, 1913.

Application filed July 1, 1909. Serial No. 505,510. Term of patent 14 years.

To all whom it may concern:

Be it known that I, OTIS A. MYGATT, residing at New York, in the county of New York and State of New York, have invented and produced a certain new, original, and ornamental Design for a Glass Shade, of which the following is a specification, reference being had therein to the accompanying drawings.

The drawing represents a perspective of the design seen from below.

The design is made of integral glass and divided horizontally into two distinct sections. The upper section is provided upon its outside with radial corrugations and upon its inner surface with horizontal corrugations. The lower section is cylindrical with vertical sides and also corrugated.

The ornamental appearance when the design is illuminated is beautiful and pleasing. The lower vertical section produces the effect of a hanging fringe of prisms in distinct contrast to the upper section. The light from this impinging upon the horizontal circumferential corrugations and transmitted thereby to the radial exterior corrugations produces a checkered animated appearance.

I claim:

The ornamental design for a glass shade, as shown and described.

OTIS A. MYGATT.
